PAPER FEED MECHANISM

Edwin L. Harmon, Groton, N. Y., assignor to L. C. Smith & Corona Typewriters, Inc., Syracuse, N. Y., a corporation of New York

Application January 16, 1939, Serial No. 251,188

12 Claims. (Cl. 197—138)

The invention relates to improvements in paper feed mechanisms, and more particularly to paper feed mechanisms for typewriting and analogous machines.

5 The principal purposes of the invention are to provide a simple, inexpensive and efficient paper feed mechanism, and to provide a paper feed mechanism consisting of a minimum number of parts, all of inexpensive construction, and the parts of which are capable of assembly without the employment of threaded holes and screws. Other purposes and advantages will be apparent from the following description of the preferred embodiment of the invention illustrated in the 10 accompanying drawings.

In the drawings:

Fig. 1 is a vertical sectional view on the line 1—1 of Fig. 3 showing the paper feed mechanism as applied to the platen carriage of a three-quarter strike or semi-front strike typewriting machine, the feed rolls being shown in "on" or working position;

Fig. 2 is a vertical sectional view on the line 2—2 of Fig. 3 showing the feed rolls cast off;

25 Fig. 3 is a top plan view illustrating the feed mechanism with the parts positioned as in Fig. 1, part of the platen and part of the paper table being broken away;

Fig. 4 is a detail sectional view on the line 30 4—4 of Fig. 3;

Fig. 5 is a detail sectional view on the line 5—5 of Fig. 3; and

Fig. 6 is a detail sectional view on the line 6—6 of Fig. 1.

35 The improvements are illustrated in connection with the platen carriage of a portable typewriting machine of the three-quarter strike variety in which the types strike at a printing point at the upper front part of the platen. The carriage comprises a sheet metal base plate 10 which is formed with raceways 11 and has rigidly affixed thereto a pair of sheet metal end plates 12. The usual roller platen 13 is journalled in the usual manner in the end plates 12 for rotation about a 40 fixed axis and is provided with the usual pair of finger wheels 14.

45 A transversely curved paper supporting and guiding table 15 formed of sheet metal, extends from its introductory end at the rear of the platen downward and forward under the platen and then upward in front of the platen to its delivery end in front of the platen. The paper table 15 is located between the end plates 12 of the carriage, and extends between the platen 50 and the base plate 10 of the carriage interme-

diate the introductory and delivery ends of the table. Formed integrally with, and extending downward and rearward from, table 15 approximately beneath the rearmost point of the platen are a pair of sheet metal pivot lugs 16. These lugs are located adjacent opposite ends of the paper table and extend edgewise of the lugs longitudinally of the table with the lugs registered edgewise longitudinally of the table. These lugs are rockably and separably seated in the forked 10 upper ends of a pair of sheet metal lugs 17 formed integrally with base plate 10 of the platen carriage. Lugs 17 extend upward and forward from the inclined base plate of the carriage toward the paper table and platen, the inclined base plate facing the rear lower quadrant of the platen. Lugs 17 are disposed edge-wise thereof transversely of the base plate and platen and in planes at right angles to those of lugs 16 on the paper table 15, and have their 20 upper ends forked or provided with notches 17a of general V-shape providing open bearings in which lugs 16 are seated and supported to rock transversely of the carriage and platen. One of the pivot lugs 16 on the paper table is provided 25 with a pair of pendent extensions 16a straddling the companion lug 17 on the carriage base plate to hold the table against movement longitudinally of the carriage and platen.

Beneath the platen the paper table is provided 30 with two parallel slots or oblong openings 18 extending longitudinally of the platen and affording clearance for a feed roll carrier and a pair of feed rolls carried by the carrier, said slots located medially with respect to the end edges of the 35 table. Slots 18 are separated by a narrow bar-like part 19 of the table, part 19 being preferably pressed or offset downward slightly from end to end thereof relatively to the portion of the table with which its ends merge, as shown.

A sheet metal feed roll carrier consisting of a single sheet metal stamping 20 and a metal supporting pin or stud 21 is removably seated and mounted on bar portion 19 for limited universal swiveling of the carrier relatively to the table. 40 Pin or stud 21 is rigidly affixed at the upper end of the pin to the carrier centrally of the carrier and depends from the under face of the carrier. Bar portion 19 of table 15 is provided with a centrally located bearing aperture 22 for pin 21, 50 said aperture being of somewhat larger diameter than the pin to permit the pin to tilt universally laterally in the aperture to a limited extent as well as to rotate in the aperture. Adjacent its upper end and at the lower face of the carrier 55

28, pin 21 is provided with an integral collar 23 which is seated rotatably and tiltably on the upper face of the bar-like part 18 of table 15 and is tapered downward to the shank of the 5 pin which passes through aperture 22. Portion 10 of the table is stiffened by integral pendent and parallel longitudinal edge flanges 19^a, and the carrier is provided with a pair of parallel and dependent longitudinal stiffening flanges 20^a somewhat more widely spaced than flanges 19^a and overlapping the latter to limit rotation of the carrier relatively to the table.

Carrier 20 is formed at each end thereof with a pair of oppositely extending arms 24 bent or 15 rolled to form semi-cylindrical open shaft bearings 24^a the open sides of which face upwardly. A pair of parallel paper feed rolls having metal shafts 25 covered by rubber sleeves 26 and having reduced end portions 25^a are mounted on the carrier by dropping the reduced end portions of the 20 shafts into the open shaft bearings 24^a and bending over the end portions of the shafts bendable extensions 24^b of the rolled semi-cylindrical bearing portions 24^a of the arms 24.

25 A rock shaft 27, formed from a narrow bar of sheet metal, extends longitudinally of the platen and carriage between the carriage base plate and the paper table and between the rear or introductory end of the table and the axis about which the 30 table is tilttable or rockable. Rock shaft 27 is formed at its ends with reduced end portions or pintles 28, one of which is journaled in a closed bearing hole 29 formed in the right hand one of the carriage end plates 12. The other pintle 28 is journaled in an open bearing 30 formed (as 35 hereinafter described) in an upstanding lug 31 bent up from the carriage base plate 10. Lug 31 is disposed edgewise thereof transversely of the carriage and is located between the left hand end 40 and the mid-length point of the carriage. The shaft bearing lug 31 is formed with the bearing slot 30 which is closed at its upper end and open at its lower end.

At the mid-length point of the carriage and 45 table, shaft 27 is bent to form the same with a substantially V-shaped crank or crank portion 32. At the mid-length point of the carriage, the carriage base plate is formed with a clearance aperture 33 for shaft crank 32, said aperture being 50 formed with a forwardly facing stop edge or shoulder 34 engageable by one side arm of crank 32 to limit rearward swinging of the crank.

55 Adjacent its right hand end and just inside of the right hand end plate of the carriage, shaft 27 is provided with a rock arm or finger piece 35 formed integrally with the shaft, and said finger piece or manually operable rock arm is movable rearwardly against a stop lug 36, bent inward from said right hand end plate of the carriage, to 60 limit rocking of shaft 27 in cast-off direction. The engagement of crank 32 of shaft 27 with stop edge 34 of aperture 33 in carriage base plate 10 limits rocking of shaft 27 in the opposite direction to apply the feed rolls. The shaft 27 is assembled in its bearings with arm 35 between lug 65 36 and the platen and with crank 32 in pendent position for swinging movement of the crank into and out of aperture 33.

A coil spring 37 of the tension pull type is connected at its opposite ends with the paper table 70 and the outer end of crank 32. The paper table is formed midway its sides adjacent its rear or introductory end and at its under face with an eye 38 pressed therefrom. The outer end or apex of 75 the V-shaped crank 32 is located midway the sides

of the table and is provided with a perforation 39. The upper end of spring 37 is hooked in table eye 38 and the lower end of spring 37 is hooked in crank perforation 39, as shown. The length of spring 37 is such that it is under tension in all 5 positions of table 15. The stops 34 and 36 which positively limit the extent of rocking movement of shaft 27 are so located that, when crank 32 is engaged with stop 34 the spring 37 extends from the table to the crank in rear of the axis of the 10 shaft (as shown in Fig. 1) to thereby yieldingly hold the feed rolls in "on" position, and when the finger piece 35 is engaged with stop 36 the spring 37 extends from the table to the crank in front of the axis of the shaft (as shown in Fig. 2) to there- 15 by hold the feed rolls in "off" position.

Upon shifting of the rock shaft from the position of Fig. 1 to that of Fig. 2, the line of pull of the spring on the table is so shifted that the pull of the spring rocks the table from the position of Fig. 1 to that of Fig. 2 and yieldingly holds the table in its position of Fig. 2 since the axial line A—A of the spring in Fig. 2 passes through the table axis and forward of the rock shaft axis. Upon manual shifting of the rock shaft back to 25 the position of Fig. 1 the pull of the spring rocks the table to the position of Fig. 1 to apply the feed rolls and yieldingly maintain them applied. In rocking between the positions of Figs. 1 and 2 the crank 32 carries the axial line of the spring at the 30 lower end of the spring across the line B—B which passes through both the table axis and the axis of the rock shaft, and also carries the axial line of the spring across the axial line of the shaft.

Spring 37, therefore, actually tilts the table 35 from one position to the other and also yieldingly holds or maintains the table in the tilted position of the table selected by manual rocking of the shaft in one direction or the other and yieldingly maintains the shaft in manually rocked position. 40 It will also be observed that the constantly tensioned spring at all times exerts pulls on the shaft 27 and table 15 to maintain the parts in assembled working relation, and that the paper table 15, spring 37, shaft 27 with its crank and finger 45 piece, the feed roll carrier 20 and the feed rolls are all assembled without the aid of screws or other extraneous fastening devices. The length of pin 21 is such that accidental disconnection thereof from aperture 22 in table 15 is prevented 50 in the cast-off position of the table and feed rolls while the platen is assembled in the carriage.

What I claim is:

1. Paper feed mechanism for typewriting and analogous machines comprising a platen carriage, 55 a roller platen journaled on and extending longitudinally of the carriage, a support extending under the platen and fulcrumed on the carriage to oscillate about an axis parallel to the platen axis, tandem feed rolls extending longitudinally 60 of the platen and carried by the support at one side of the axis about which the support oscillates for movement of the rolls into and out of paper feeding relation with the platen by oscillation of the support, a manually rockable rock shaft 65 journaled on the carriage and extending longitudinally of the platen at the opposite side of said axis of oscillation of the support and at the opposite face of the support from that at which the platen is located, said shaft having a crank 70 extending therefrom to rock therewith, means for limiting rocking movement of said shaft in both directions about its axis, and a tension pull spring connected at opposite ends of the spring to said support and to said crank to extend be- 75

5 between the support and crank at different sides of the shaft axis in different manually oscillated positions of said shaft, said spring being connected to the support at that side of the axis of oscillation of the support at which said shaft is located.

10 2. Paper feed mechanism for typewriting and analogous machines comprising a platen support, a roller platen journalled on said support to rotate about a fixed axis, a paper table extending part way about said platen and mounted on said support to tilt about a fixed axis which is parallel to the platen axis, a rock shaft journalled on the support for oscillation about a fixed axis which is parallel to said two previously mentioned axes, said table extending between said shaft and platen, said shaft having a crank, a pull spring connected to said table and to said crank to be carried across the axis of the shaft by oscillation of the shaft to tilt the table in opposite directions and yieldingly hold it tilted, and manually operable means connected with the shaft for oscillating the shaft.

15 3. Paper feed mechanism for typewriting and analogous machines, as claimed in claim 2, wherein in the platen support is provided with a set of open bearings, and the table is provided with a set of pivot elements held seated in said open bearings by the pull exerted on the table by said 20 pull spring.

25 4. Paper feed mechanism for typewriting and analogous machines, as claimed in claim 2, wherein in the platen support is provided with one closed and one open bearing for said rock shaft, said 30 shaft is provided with pintles engaged in said bearings, and the shaft pintle engaged in the open bearing is held therein by pull exerted on said shaft by said pull spring.

35 5. Paper feed mechanism for typewriting and analogous machines comprising a platen support, a roller platen journalled on said support to rotate about a fixed horizontal axis, a paper table mounted on said support to tilt about an axis parallel to the platen axis and extending under 40 the platen to one side of the axis about which the table is tilttable, a feed roll carrier mounted on said table under the platen to rotate about an upstanding universally tilttable axis, a pair of parallel feed rolls journalled on said carrier and 45 extending longitudinally of the platen, and manually operable means for tilting said table to apply said feed rolls to and cast them off from the platen.

50 6. Paper feed mechanism for typewriting and analogous machines comprising a platen support, a roller platen journalled on said support to rotate about a fixed horizontal axis, a paper table mounted on said support to tilt about an axis parallel to the platen axis and extending 55 under the platen to one side of the axis about which the table is tilttable, a feed roll carrier mounted on said table under the platen to rotate about an upstanding universally tilttable axis, a pair of parallel feed rolls journalled on said carrier and 60 extending longitudinally of the platen, and manually operable means for tilting said table to apply said feed rolls to and cast them off from the platen, said table and carrier having means engageable to limit rotation of the carrier about 65 said upstanding axis.

70 7. Paper feed mechanism for typewriting and analogous machines comprising a platen support, a roller platen journalled on said support to rotate about a fixed axis, a paper guiding table mounted on said support to tilt about an axis

parallel to the platen axis, tandem feed rolls carried by the table for guiding of paper between the platen and said rolls by the table and for application of said rolls to and casting off of said rolls from the platen by tilting of the table, a 5 manually rockable crank shaft journalled on said support for rocking of said shaft about an axis parallel to the platen axis and the axis about which the paper table is tilttable, means for positively limiting the extent of rocking movement 10 of said shaft, and a tension pull spring connected at its opposite ends to said table and to the crank portion of said crank shaft to tilt the table to apply and cast off the feed rolls upon rocking of said shaft to different ones of 15 its limits of rocking movement.

8. Paper feed mechanism for typewriting and analogous machines comprising a platen support, a platen journalled on said support for rotation about a fixed axis, a paper table mounted on said support to extend part way about said platen, a feed roll carrier mounted on the paper table for limited rotation about an axis extending transversely of the platen and for limited universal tilting of the carrier relatively to said last-mentioned axis, and a pair of parallel feed rolls journalled on the carrier to extend substantially longitudinally of the platen for feeding of paper between the platen and said rolls.

9. Paper feed mechanism for typewriting and analogous machines comprising a platen support, a roller platen journalled on said support to rotate about a fixed horizontal axis, a paper table mounted on said support to tilt about an axis parallel to the platen axis and extending under 35 the platen to one side of the axis about which the table is tilttable, a feed roll carrier mounted on said table under the platen to rotate about an upstanding universally tilttable axis, a pair of parallel feed rolls journalled on said carrier and extending longitudinally of the platen, and manually operable means for tilting said table to apply said feed rolls to and cast them off from the platen and including spring means connected to the said table to yieldingly hold the feed rolls when applied in paper feeding relation to the platen, said table and carrier having means engageable to limit rotation of the carrier about 40 said upstanding axis.

10. Paper feed mechanism for typewriting and analogous machines comprising a platen support, a roller platen journalled on said support for rotation about a fixed axis, a rock shaft extending longitudinally of the platen, said rock shaft having reduced pintle end portions and formed between its ends with a crank portion, said support being provided with a closed bearing and an open bearing for the respective pintle end portions of said rock shaft, a paper guiding table extending between the platen and both said support and rock shaft and carrying paper feed rolls adapted to engage the platen, said support being provided intermediate said shaft and the delivery end of the table with open bearings and said table being provided intermediate said shaft and the delivery 55 end of the table with pivot elements engaged in said open bearings to support the table to tilt about a fixed axis extending longitudinally of the platen, and a tension pull spring connecting the introductory end of the table and the crank portion of the rock shaft to tilt the table to cast the rolls respectively on and off upon rocking of the shaft in opposite directions and to constantly hold said shaft in its bearings and also hold the pivot elements of the table engaged in the open 60 70 75

bearings therefor on the support, said shaft being formed with a manually operable rock arm for rocking the shaft.

11. Paper feed mechanism for typewriting and analogous machines comprising a platen support, a roller platen journaled on said support to rotate about a fixed horizontal axis, a paper table mounted on said support to tilt about an axis parallel to the platen axis and extending under the platen to one side of the axis about which the table is tiltable, a paper feed roll carrier having rigidly fixed thereto and pendent therefrom centrally thereof a pivot pin extending downward from the carrier through an aperture in said table and of sufficiently smaller diameter than said aperture to permit limited tilting of said pivot pin in said aperture, said pin having a downwardly tapering collar seated on the table, a pair of parallel feed rolls journaled on the carrier and extending longitudinally of the platen to engage the platen forward of the axis about which the table tilts, said table having clearance openings for said feed rolls and carrier, said table and feed roll carrier being provided with means 25 limiting rotation of the carrier relatively to the table, and said platen being engageable by the

rolls to block accidental withdrawal of said pin from said aperture in all tilted positions of the table.

12. Paper feed mechanism for typewriting and analogous machines comprising a platen support, a roller platen journaled on said support, a paper support extending under the platen and fulcrumed on the platen support to oscillate about an axis parallel to the platen axis, feed rolls carried by the support at one side of the axis about which the support oscillates for movement of the rolls into and out of paper feeding relation with the platen, a manually oscillatable control member to move the paper support and thereby shift the feed rolls into and out of paper feeding relation to the platen and journaled on the platen support at the opposite side of said axis of oscillation of the paper support, and a tension pull spring connected at opposite ends of the spring to said paper support and to said control member to extend between the said support and the control member at different sides of the journal of said control member in different manually oscillated positions of said member.

EDWIN L. HARMON. 2
